UNITED STATES PATENT OFFICE.

JOHN HEADLAND, OF GALVA, ILLINOIS.

DOOR-OPENER.

SPECIFICATION forming part of Letters Patent No. 584,588, dated June 15, 1897.

Application filed May 11, 1895. Serial No. 548,897. (No model.)

To all whom it may concern:

Be it known that I, JOHN HEADLAND, a citizen of the United States, residing at Galva, in the county of Henry and State of Illinois, have 5 invented certain new and useful Improvements in Door-Openers, of which the following is a specification.

My invention relates to foot-operated door-openers.

10 The nature of the invention, the objects thereof, and the construction and organization of the parts as embodied in a working door-opener are hereinafter described, and the combinations of parts in which the improvements consist are also hereinafter described and made the subject-matter of claims hereto appended.

In the accompanying drawings all my improvements are shown as embodied in the 20 best way now known to me. Obviously, however, while still within the purview of my invention, some of these improvements may be used without the others and in door-openers differing in construction and organization of 25 parts from the door-opener described and shown by me.

In the drawings, Figure 1 is a perspective showing part of a door in a closed position, parts of the wall adjacent to each side of the 30 door, and my improved door-opener in place on the door; Fig. 2, an edge elevation of part of the door in an open position and sectional elevation of adjacent parts of the wall and base-board or skirting-board, oblique elevation of the door-jamb, and side elevation of the door-stop; Fig. 3, an edge elevation of the lower part of the door and side elevation of the lower part of the door-opener and the foot of a person in place for operating it; Figs. 4 35 and 5, side elevations, partly in section, of the latch-operating crank-arm and sectional elevation of the door-knob or lock-spindle and knob-shank.

The swinging door A, wall a, skirting-board 45 a', door-casing a'', hinges a'', and lock B may be of any ordinary construction to which my improvement is applicable.

The foot-piece C, by means of which the latch b of the lock B is operated, as herein-after described, consists of side bars c', bent

outwardly at their lower ends and connected by a bar c''. The side bars c' are slidably mounted in bearings c'', which project from a plate c', fixed to the door A by screws c''. A shield c'' is preferably interposed between the 55 plate c' and the door and extends downwardly to such an extent as to protect the door from abrasion by the shoe or boot on the foot of the operator. The part or bar c'' is preferably covered by a rubber sleeve c'''.

60 The crank-arm D is bifurcated at its lower end and strides the shank b' of the lock-knob b'', thereby striding the spindle b'' of the lock, to which parts b' and b'' it is secured by a bolt d, which passes through shank and the 65 spindle. The outer end of the arm D extends laterally and by preference upwardly from the spindle b''. This arm D is, further, of such construction or bent in such manner that it may be fixed to the spindle by a vertical bolt 70 d, as shown at Fig. 4, or by a horizontal bolt, as shown at Fig. 5, and in both of said positions the crank-arm will project to about the same point relatively to the spindle b''. The spindle b'' is an ordinary rocking spindle and 75 is turned by the knob b'' in an ordinary manner in one direction to retract the lock-latch b and is turned in an opposite direction by a spring d'' in an ordinary manner. A chain, cord, or link E is connected at its upper end 80 to the outer end of the arm D, and its lower end is bifurcated and is connected one branch e thereof with the upper end of each side bar c'.

Assuming the door to be in its closed position, as shown at Fig. 1, the operator, by 85 placing his foot on the bar c'' and pressing thereon, will, through the instrumentality of the slidable foot-piece C and chain E, draw down the outer end of the arm D and thereby turn the spindle b'' in a direction to retract 90 the latch b and permit the door to be opened. By placing the foot in the inclined position shown by full lines at Fig. 3 such force as is necessary to pull it open may be advantageously applied. The pressure of the foot on 95 the bar c'' being removed the spring d'' will force the latch b out into its normal position and thereby turn the spindle b'' in an opposite direction to that last described.

In closing the door the foot of the operator 100

can be inclined, as shown by dot lines at Fig. 2. A similar door-opener may be placed on the other side of the door.

By the means described the operator may 5 both open and close the door from either side.

In order to render the opener more certainly effective, and more particularly to aid the spring d^2 in throwing out the latch against the extra resistance arising from its having 10 to raise the main parts of the opener, I have located a helical spring G above the outer end of the arm D and fixed its upper end to the door and its lower end to the outer end of said arm D. When the parts of the opener 15 are in their normal positions, as shown at Fig. 1—that is, the foot-piece C in its highest position and the latch b thrust out—the adjustment of the tension of the spring G is such that it will either exert no upward force on 20 the arm D or so small an amount as to not lift the arm D, chain E, and foot-piece C. When the foot-piece C is forced downward to retract the latch b, as hereinbefore described, the spring G will be acted on by the arm D 25 and its coils be more separated. The spring G thus becomes an auxiliary to assist the lock-spring d^2 and a substitute for the spring d^2 in case of its breaking or failure. The spring G may be a spring of any other class 30 or type, if desired.

I is an ordinary door-stop of the class having a hook-shaped catch i on its outer end and fixed at its other end to the skirting-board. When the door is thrown entirely open, the

bar c^2 will engage with the hook i and hold 35 the door open. The bar c^2 can be released from the hook i for closing the door by forcing the foot-piece C downwardly by the foot (see dotted lines at Fig. 2) or by turning the knob b^2 with the hand in a direction to retract the latch b and thus allow the chain E 40 and foot-piece C to fall to their lower positions.

Having thus described my invention, what I claim as new, and desire to secure by Letters Patent, is—

1. In a door-opener, and in combination substantially as described, a door, a spring-actuated latch, a slideable foot-piece having side bars c' with outwardly-turned lower parts connected by a bar c^2 , bearings c^3 for the side 50 bars c' , a lock-spindle, an arm D fixed to and projecting from said lock-spindle, and means for connecting the foot-piece and said arm.

2. In a door-opener, and in combination, a spring-actuated latch, a slideable foot-piece, 55 a lock-spindle, a bent arm which may be fixed by a horizontal or vertical bolt to the lock-spindle to project to substantially the same point, and means for connecting said arm and the slideable foot-piece, substantially as de- 60 scribed.

In testimony whereof I affix my signature in presence of two witnesses.

JOHN HEADLAND.
